United States Patent Office

GOTTLIEB HENNING AND HERMAN P. WILLIE, OF BUFFALO, NEW YORK.

Letters Patent No. 73,328, dated January 14, 1868.

IMPROVED BOOT-HEEL.

The Schedule referred to in these Letters Patent and making part of the same.

TO ALL WHOM IT MAY CONCERN:

Be it known that we, GOTTLIEB HENNING and HERMAN P. WILLIE, both of the city of Buffalo, in the county of Erie, and State of New York, have invented a new and improved Heel for Boots and Shoes; and we do hereby declare that the following is a full and exact description thereof, reference being had to the accompanying drawings, in which—

Figure 1 is a perspective view of our improvement, a portion of the rubber covering being removed to show the frame A.

Figure 2 is a plan of the frame A detached.

Figure 3 is an elevation of a heel, a part being shown in section.

Like letters indicate corresponding parts in the several figures.

Our invention consists of a metallic skeleton-frame, having a flanged exterior rim, said frame being, with the exception of the rim, embedded in India rubber, and provided with a fixed screw, whereby, together with other screws, it is attached to the boot or shoe.

As represented in the drawings, the frame A is shown separately in fig. 2. The bars *b b*, which may be more or less in number, are on a horizontal plane, placed centrally of the depth of the rim *c*, leaving a flange extending both above and below the bars, which serves to limit the lateral expansion of the rubber, restricting it to the size of the heel. The rim is finished on its outer surface to correspond with the shape of the heel, the lower portion of the same, *d*, being built up of leather in the usual manner. Centrally of the rear of the frame, a screw, *e*, is permanently affixed, by casting or otherwise, and in front, two or more holes, *f f*, for loose screws, are provided.

The frame so constructed is placed in a suitable mould, and India rubber in a melted state is introduced, which forms around it, leaving only the exterior surface of the rim uncovered. The rubber is cast flush with the edge of the flange or rim on the side which joins the leather heel; but on the other or tread-surface, *g*, it is made of any degree of thickness, which service may require, varying according to the size and kind of boot to which it is applied. In attaching to the boot, the fixed screw *e* is inserted in a hole, made at the proper place in the leather heel, and screwed in by turning the frame, until it is brought down to the leather, when the additional loose screws are inserted through holes *f f*, which may be located at any part of the front side, securing it permanently. The leather is trimmed down to the size of the rim, and the heel polished.

We are aware that metallic plates have been employed, and also metallic rims or sockets, for applying a rubber block to the outside of the heel; but these forms are objectionable, as being too rigid, liable to break, and too heavy, from the weight of metal required by them. The elasticity of the rubber is in a measure impaired by a solid plate of metal intervening between it and the leather; but in our invention we secure the utmost lightness, by means of the skeleton-frame, retain the elasticity by having the major part of the rubber rest on the leather, itself a partially-elastic substance, while the rubber is effectually prevented from spreading by the flanges of the rim, which encircle it both above and below the bars. The permanently-attached screw *e* also affords a more effectual mode of correctly applying and securely attaching to the boot than has hitherto been used.

What we claim as our invention, and desire to secure by Letters Patent, is—

A boot-heel, consisting of the embedded skeleton-frame A, provided with the flanges on the rim *c*, fixed screw *e*, and rubber *g*, constructed and arranged substantially as set forth.

In witness whereof, we have hereunto signed our names in the presence of two subscribing witnesses.

GOTTLIEB HENNING,
HERMAN P. WILLIE.
